(57) **CLAIM**

We claim the ornamental design for a condiment carousel, as shown and described.

DESCRIPTION

FIG. 1 is a perspective view of a condiment carousel showing our new design;

FIG. 2 is a side elevational view thereof; all other side elevational views being substantially identical thereto;

FIG. 3 is a top plan view thereof;

FIG. 4 is a bottom plan view thereof; and,

FIG. 5 is a reduced perspective view showing the condiment carousel in use; the broken lines depict environmental structure for illustrative purposes only and form no part of the claimed design.
